UNITED STATES PATENT OFFICE.

PERCY H. THOMAS, OF MONTCLAIR, NEW JERSEY, ASSIGNOR, BY MESNE ASSIGNMENTS, TO COOPER HEWITT ELECTRIC COMPANY, OF HOBOKEN, NEW JERSEY, A CORPORATION OF NEW JERSEY.

OPERATION OF VAPOR-CONVERTERS.

1,110,588.

Specification of Letters Patent. Patented Sept. 15, 1914.

Application filed September 1, 1905. Serial No. 276,672.

To all whom it may concern:

Be it known that I, PERCY H. THOMAS, a citizen of the United States, and resident of Montclair, county of Essex, State of New Jersey, have invented certain new and useful Improvements in the Operation of Vapor-Converters, of which the following is a specification.

In certain applications for Letters Patent 10 of the United States, namely, application Serial Number 140,353, filed January 24, 1903, and application Serial Number 155,923, filed May 6, 1903, I have shown and described a system of supplying constant current 15 to direct current translating devices from an alternating current source through the medium of one or more vapor converters.

The object of the present invention is to provide certain improvements in the system 20 described in said applications, such improvements relating to features which will be described hereinafter and more particularly pointed out in the claims attached hereto.

The present invention contemplates, 25 among other things, the application of the system of distribution to cases where extremely high potentials are used and where a single vapor converter of the design and construction most naturally applicable 30 would be incapable of economically supporting the full potential strain. Under these conditions I introduce one or more additional converters so arranged that the voltage delivered on the direct current side of 35 the converter shall be additive, allowing the use of a higher resultant voltage upon the operating and receiving circuits.

My invention further contemplates the 40 application of the principles recited above to polyphase supply circuits; while at the same time it contemplates the simplification of the means for impressing constant alternating current upon the vapor devices. Such means may consist of suitable ballast 45 devices, or of special apparatus, preferably automatic, for connecting the vapor device or devices to points of different potential in the supply circuit.

The invention may also be applied to 50 circuits in which the regulator is placed directly in the leads to the positive electrodes.

My invention is illustrated in the accompanying drawing, which shows an applica-

tion of my invention for the combining of three transformer secondaries in series for 55 supplying a direct current circuit and which shows certain suitable starting connections therefor.

Referring to the figure of the drawing, 1 is the primary of a transformer, the terminals of which are connected to a source of alternating current through a reactance regulator of the type disclosed in certain patents to Malcolm H. Baker; for example, United States Patents 684,165, 684,340 and 65 684,342, issued on the 8th day of October, 1901. It is well understood that these regulators relate to means and methods whereby a reactance coil acts in opposition to a counter weight which is so correlated to the magnetic pull of the coil that the choking effect of the coil will vary automatically to compensate for changes of resistance in the receiving circuit. I have thought it sufficient to indicate the Baker regulator by the character 2, indicating more particularly the coil of the said regulator. It will be understood, however, that the reference numeral includes also the counter weight which is opposed to the pull of the coil for the purpose indicated. 70 For greater clearness I designate the counter weight and the intervening apparatus by the 75 numeral 100.

The primary 1 is in operative relation to three secondary windings, 3, 4, and 5, connected, respectively, at their terminals to the positive electrodes, 9, of vapor converters, 6, 7 and 8. Intermediate points of the secondary are connected to the negative electrodes, 10, 10, 10, of the said converters through 80 starting devices, 11, consisting in the form shown of reactances 111, 111, 111, and resistances, 112, 112, 112. The connection also passes through inductances, 12, 12, 12, with interposed switches 13, 13, 13, for opening 95 the circuits to the negative electrodes 10, 10, 10.

Auxiliary resistances, 14, 14, 14, are connected between one or more of the positive electrodes 9 of each converter and supplementary electrodes, 15, 15, 15. The load circuit 16 including constant current consumption devices such as arc lamps 17, 17, 17, are connected in series with an impedance, 18, capable of being short-circuited by a 105 switch, 19. By means of cross-connections,

20, 20, the several converters are connected in series as will be seen by an analysis of the circuits in the figure.

- 5 The operation of starting the several converters is brought about by first tilting the said converters with the switches 13, 13, 13, closed, so as to bring into contact the mercury or other conducting fluid of the electrodes 10 and 15 and then tilting the converters back again so as to restore them to their original positions, thereby breaking the connection between the said electrodes and causing current to flow between them. This operation of vapor devices is already 10 well understood as is also the function of resistances, 14, 14, 14, which are connected as described above between one or more of the positive electrodes, 9, 9, and the supplementary electrode 15 of each converter.
- 15 20 When all the converters have been started in the manner described or in any other suitable way, potential is established between the terminals of the work circuit 16, and current flows through this circuit sufficient 25 to energize the various translating devices therein. The switches 13, 13, 13, may then be opened and the apparatus is thereupon placed in condition for continuous operation.

I prefer to provide common means for 30 tilting the converters, such means consisting of a bar or lever, 21, pivoted at any suitable point and provided with a suitable handle, 22.

The switches 13, 13, 13, are automatically 35 operated by the coil 18 upon the establishment of normal current in this coil, through the member 141, the said member being actuated by the armature 140, placed in operative relation to the coil 18. The attraction 40 of the coil 18 upon the armature 140, resulting from the establishment of current in the said coil raises the armature 140, opening the switches 13 and thus discontinuing the starting circuits.

45 By virtue of the series arrangement of converters shown, the total potential applied to the converters and received by the consumption circuit may be considerably greater than would be practicable with a 50 single converter, and much higher potentials can be employed in the system than would otherwise be permissible.

It is evident that the system shown may be utilized on constant potential circuits as 55 well as constant current circuits.

Certain aspects of the present invention are claimed in a number of divisional applications hereof, namely, applications bearing the Serial Nos. 447,409, filed August 7, 1908; 60 447,410, filed August 7, 1908; 398,708, filed October 23, 1907.

I claim as my invention:

1. The combination of a plurality of vapor converters having suitable electrodes, 55 supply transformer windings, connections

between said converters and said transformer windings and series connections between said converters, with starting circuits for the several converters, together with automatic means for discontinuing said starting circuits. 70

2. The combination of a plurality of serially connected vapor converters, an alternating current supply circuit and a work circuit, with an inductive starting shunt controlled by resistance connected across the load circuit. 75

3. In a system of electrical operation the combination of a plurality of vapor converters including exhausted containers and adapted to be started by mechanical movement thereof, and motion-permitting mountings for said containers, with means for producing simultaneous movement of the said containers together with series connections between the converters, starting connections and automatic means for interrupting said starting connections upon the initiation of normal operation. 80

4. In a system of electrical distribution, constant current translating devices supplied from an alternating current source, vapor converters, individual means for starting the vapor converters constituting as a whole a shunt across the work circuit and means for connecting in series electromotive forces derived from the said vapor converters for supplying said translating devices. 90

5. In a system of electrical distribution, the combination with a plurality of mercury vapor rectifiers, each including an exhausted container and a vaporizable cathode and suitable alternating sources therefor, of a work circuit, series connections between the rectifiers, each connection including an inductance, and connections between the rectifiers and the work circuit, together with separate starting shunts around the several rectifiers. 100

6. In a system of electrical distribution, the combination with a plurality of mercury vapor rectifiers, each including an exhausted container and a vaporizable cathode, and suitable alternating sources therefor, of a work circuit, series connections between the rectifiers, each connection including an inductance, and connections between the rectifiers and the work circuit, together with separate starting shunts around the several rectifiers, together with means for simultaneously opening the several starting shunts. 115

7. In a system of electrical distribution, the combination with a work circuit, a plurality of mercury vapor converters, each including an exhausted container, a vaporizable liquid cathode, and a starting anode operating therewith and connected with the lead of a main anode also in the container, and suitable alternating supply 125 130

sources and connections therewith, of means for simultaneously tilting the several containers thereby closing a metallic circuit between the cathodes and the starting anodes simultaneously in the various converters, whereby a continuous starting circuit including the work circuit and a portion of the several alternating sources is formed.

Signed at New York, in the county of New York and State of New York, this 28th 10 day of August A. D. 1905.

PERCY H. THOMAS.
